UNITED STATES PATENT OFFICE

2,553,057

LABEL AFFIXING MACHINE

Vincent Lobasso, New York, N. Y.

Application August 11, 1950, Serial No. 178,803

12 Claims. (Cl. 216—57)

1

This invention relates to improvements in label affixing machines, and, more especially, to improvements in machines for applying labels about readily deformable articles such as balls of yarn, twine and the like.

In my Patent No. 2,504,993, issued April 25, 1950, there is disclosed a machine for applying labels about readily deformable articles, which machine includes specially designed holder elements preventing excessive deformation of the article during the label affixing operation. The holder elements are mounted on an intermittently actuated chain or wheel conveyor and the articles to be labeled are successively conveyed to a label affixing station where a label is extended about both the article and the holder element upon which it is supported, the labeled article being subsequently ejected from its holder element at a point remote from the label affixing station by a throwout or ejection mechanism.

In my co-pending application Serial No. 111,138, filed August 19, 1949, there are disclosed certain improvements over my above-identified patent, including improved design of holder elements, ejection mechanism and novel cushioning or stop means serving for more accurate and efficient alignment at the label affixing station of the loaded holder elements carried on the intermittently actuated conveyor of the machine. The present application is concerned with further improvements over the devices described in my above identified patent and co-pending application and constitutes a continuation-in-part of my co-pending application.

A primary object of the present invention is the provision of a label affixing machine which is specifically designed to utilize the deformable characteristics of the article to be labeled as a positive and advantageous factor insuring rapid, secure and efficient labeling, such deformability having been considered troublesome, disadvantageous and a factor to be neutralized or overcome mechanically in previous attempts to devise a machine for labeling deformable articles.

A further and more specific object of the invention is the provision of a machine of the character indicated wherein a label may be extended about a deformable article retained upon its holder element at the label affixing station of the machine, after which a pair of reciprocating guides or jaw members press against opposite portions of the label to compress or deform the article somewhat and cause the label to conform closely to the contour of the article prior to securing the ends of the label together.

2

Another object of the invention is the provision of a machine of the character indicated having improved ejection mechanism adapted to act simultaneously upon both the secured label and the deformable article retained upon the holder element in order to more expeditiously eject the labeled article from the holder element.

The foregoing objects as well as additional objects and advantages of the invention will be readily apparent in the course of the following detailed description taken in connection with the accompanying drawings which illustrate a preferred embodiment of the invention, and wherein:

Fig. 1 is a top plan view of a portion of a machine embodying the features of the invention and illustrates the reciprocating jaw members disposed at the label affixing station thereof;

Fig. 2 is a sectional view taken substantially along line 2—2 of Fig. 1;

Fig. 3 is a sectional view taken substantially along line 3—3 of Fig. 1;

Fig. 4 is a front elevational view of one of the improved holder elements;

Fig. 5 is a bottom plan view of the holder element;

Fig. 6 is a top plan view of the holder element;

Fig. 7 is a front elevational view of the improved ejector mechanism disposed at the ejecting station of the machine; and

Fig. 8 is a side elevational view of the ejector mechanism.

Fig. 9 is a front elevation of the machine embodying the features of the invention.

The drawings illustrate only those novel elements of the label affixing machine which constitute improvements over my Patent No. 2,504,993 and my co-pending application Serial No. 111,138, previously referred to.

It will be understood that the machine may embody the features disclosed in my Patent No. 2,504,993 and my copending application with respect to the arrangement for feeding the articles successively to the label affixing station of the machine and with respect to the arrangement

for actuating the ejector mechanism at the ejecting station of the machine. By way of summary it will be stated that the present invention contemplates the use of an intermittently actuated conveyor system or equivalent including a plurality of individual holder elements upon which the deformable articles to be labeled may be supported. Each article supported on a respective holder element is conveyed in a stepwise manner to the label affixing station where a label is extended about both the article and the

holder arms during the rest period of the conveyor. Each holder element is preferably provided with an auxiliary retaining member or arm which is normally urged against the upper tiltable holder arm. Trip means are provided in order to assure automatic elevation of the auxiliary retaining member when a given holder element is disposed at the label affixing station of the machine so that the label may be properly and unobstructedly applied about the article and the main upper and lower holder arms. After the label has been applied and the overlapping ends of the label have been secured together, the labeled article on its holder element moves away from the affixing station and the auxiliary holding member operates to maintain the overlapped ends of the label in secure engagement during the interval of movement of the conveyor between the label affixing station and the ejecting station of the machine. The mechanism for extending, overlapping and securing the label is described in my Patent No. 2,179,264, issued November 7, 1939 and will not be detailed here since it does not form the subject matter of the present invention.

A major feature of the present invention resides in specifically designing the machine to utilize the deformable characteristics of the article to be labeled as a positive and advantageous factor insuring rapid, secure and efficient labeling. It is well known to those skilled in the art that the application of labels to deformable articles such as balls of yarn presents special problems and difficulties which are not encountered with relatively rigid and shape-sustaining articles since the former are readily distorted and do not ordinarily retain a fixed, predetermined shape allowing a label to be extended thereabout and to be firmly retained thereon. The present invention overcomes the problem of deformability by the provision at the label affixing station of a pair of reciprocating guides or jaw members which are adapted initially to retain a label pending the arrival at the affixing station of a holder element loaded with a deformable article, and subsequently to press against opposite portions of the label extended circumferentially about the article to compress or deform the article somewhat, thereby causing the label to conform closely to the slightly reduced contour of the article prior to securing the overlapped ends of the label together. Upon retraction of the jaw members after the ends of the label have been secured together, the article will expand slightly with the result that the label will be securely retained in affixed position.

Another feature of the present invention resides in the provision of an improved ejector mechanism adapted to act simultaneously upon both the secured label and the deformable article retained upon the holder element in order to more expeditiously eject the labeled article from the holder element.

The foregoing features as well as additional features of the invention will now be described in detail with reference to the accompanying drawings.

Referring first to Figs. 1 to 3 of the drawing which illustrate the construction and operation of the reciprocating guides or jaw members disposed at the label affixing station of the machine, the machine includes a pair of fixed frame elements 10 through each of which extend a pair of hollow sleeves or guides 11 fixed in position by set screws 12. Spaced inwardly of frame

elements 10 and adjustably retained on sleeves 11 by means of set screws 13 are a pair of mounting or spacing blocks 14.

A pair of reciprocating jaw members, generally designated by reference numeral 15, are disposed at the label affixing station of the machine and said jaw members are arranged to reciprocate during the rest period of the machine conveyor (not shown) when a holder element H carrying a deformable article such as a yarn ball Y is disposed between said jaw members at the labeling station of the machine, as shown in Fig. 3. Each of the jaw members 15 may comprise a vertical mounting plate 16 to which is firmly secured a pair of rods 17 slidably retained within hollow sleeves 11. At their outer ends rods 17 are rigidly interconnected to move in unison by means of a cross bar or connecting bar 18. Jaw members 15 are normally urged apart against mounting blocks 14 in the position of Figs. 1 and 2 by means of compression springs 19 interposed on each rod 17 between cross bar 18 and the outer end of a respective sleeve 11.

Companion plate 20 is preferably welded to each vertical mounting plate 16 in order to serve for retaining a hinge plate 21. Hinge plates or deflector plates 21 are normally retained in substantially horizontal position as shown in Figs. 30 1 and 2 by means of relatively light tension springs 22. Each hinge plate 21 is preferably provided at its front and rear portion with an integral lateral extension 21a adapted to be retained against recessed terminal abutment shoulders 14a formed in mounting blocks 14. In order to cushion the return movement of hinge plates 21 under the influence of return springs 22 after the passage of a labeled article on its holder elements from the label affixing station 40 of the machine, each abutment shoulder may be provided with a spring-backed plunger 23 to take up the impact of hinge plate extension 21a, as best shown in Fig. 2.

The advancement and retraction of reciprocable jaw members 15 may be controlled in any desired manner, as by means of a cam 30 (see Fig. 1) mounted on cam shaft 31 and which actuates a rocker arm 32 carrying a follower 33 constantly urged against said cam by means of a spring (not shown). It will be understood that rocker arm 32 may be pivoted at its lower end to a fixed frame portion of the machine and is operatively connected at its upper end to a reciprocating bar 34 suitably mounted on the frame of the machine. As seen in Fig. 1 reciprocating bar 34 is provided at its end opposite rocker arm 32 with an angularly inclined extension or arm 35. Extension 35 is of suitable length and shape to terminate substantially intermediate cross bar 18 controlling jaw member 15 on the left side of the machine in the normally separated position of jaw members 15 illustrated in Figs. 1 and 2. A roller 36 is preferably carried at the free end of extension 35 in order to abut left-hand cross bar 18 and urge said cross bar and left-hand jaw member 15 inwardly when reciprocating bar 34 is moved to the right as seen in Figs. 1 and 2.

Simultaneously with the advancement of left-hand jaw member 15 in the manner described, the right-hand jaw member 15 is caused to advance or move inwardly toward said left-hand jaw member. For this purpose a connecting lever 37 is pivoted intermediate its ends at 37a to a fixed frame bracket 38, as shown in Fig. 1 and is also pivoted at its forward end at 39 to a hori-

zontal extension 40 of reciprocating bar 34. Lever 37 is of sufficient length to terminate substantially intermediate right-hand cross bar 18 and carries a roller 41 in order to abut and urge said right-hand cross bar 18 and right-hand jaw member 15 inwardly simultaneously with the advancement of left-hand jaw member 15.

By reason of the novel construction and arrangement of the present invention, hinge plates 21 of jaw members 15 are normally held in horizontal position, as shown in Fig. 2, thereby serving to retain a label at the label affixing station pending the arrival thereat of a holder element H loaded with a yarn ball Y or the like. As the loaded holder element H is brought to its rest position at the label affixing station of the machine, hinge plates 21 are progressively deflected downwardly until they finally assume a substantially vertical position coplanar with the plates 20, as clearly shown in Fig. 3. At this point in the operation of the machine, cam 39 is actuated in order to urge jaw members 15 together, thereby compressing the yarn ball Y and simultaneously pressing against opposite sides of the partially extended label L to cause the label to conform closely to the slightly reduced contour of the yarn ball prior to securing the overlapped ends of the label together. Upon retraction of the jaw members 15 after the ends of the label have been secured together, the yarn ball will expand slightly with the result that the label will be securely retained in affixed position.

In order to assure unobstructed passage of the labeled article on its holder element from the label affixing station, means are provided for temporarily arresting the return movement of hinge plates 21 to the normally elevated, substantially horizontal position of Fig. 2. For this purpose each hinge plate 21 is provided on its underside with a bracket 45 carrying a laterally extending pin 46. A left-hand angular hook member 47 and a right-hand angular hook member 48 are arranged in such a manner as to engage the pins 46 of respective hinge plates 21 when said hinge plates assume their completely deflected vertical position of Fig. 3. Hook members 47 and 48 may be pivotally supported on bracket members 49 secured to respective mounting plates 16 of jaw members 15. Left-hand hook member 47 is normally urged downwardly in a clockwise direction by means of a tension spring 50 and right-hand hook member 48 is normally urged upwardly in a clockwise direction by means of a tension spring 51. Each of the hook members 47 and 48 is provided with a laterally extending trip rod 47a and 48a which extends into operative engagement with depending abutment members 52 formed on a slidable horizontal releasing or trip bar 53 suitably mounted on the frame of the machine. Trip bar 53 is operatively connected at one end as by means of a pin 54 with a slot 55 formed in a rocker arm 56 which may be pivoted at its lower end (not shown) to the frame of the machine. Said rocker arm and trip bar are actuated by a releasing cam 57 mounted on cam shaft 31 in order to move hook members 47 and 48 out of restraining engagement with respective pins 46 of hinge plates 21 thereby causing said hinge plates to move from their completely deflected position of Fig. 3 to their normally elevated, substantially horizontal position of Fig. 2. Rocker arm 56 carries a follower 58 which is maintained in constant abutment engagement with releasing cam 57 by means

of a tension spring 59 (see Fig. 2) interconnecting said rocker arm with the frame of the machine. It will be understood that the actuation of trip bar 53 will urge the depending abutment members 52 against trip rods 47a and 48a of hook members 47 and 48 and will move said hook members out of restraining engagement with respective pins 46 of hinge plates 21 by overcoming the tension of springs 50 and 51 respectively. The timing of releasing cam 57 is so synchronized with the movement of the holder elements H that release of hook members 47 and 48 will occur only after a given holder element H containing a labeled article has passed from the label affixing station and cleared the lower extremities of the completely deflected hinge plates 21.

Referring now to Figs. 4, 5 and 6, my improved holder element H includes a main plate 65, which may be suitably secured to a conveyor mechanism (not shown), a lower adjustable arm 66 slidably mounted on said main plate and a tiltable upper arm 67 pivotally mounted on said main plate at 68 by means of a rearward extension 67a which carries at its free end a roller 69 adapted to be engaged by suitable auxiliary means (not shown) for elevation of said upper arm during loading of the holder element and for lowering said upper arm to closed position when the loaded holder element arrives at the label affixed station of the machine. Such auxiliary means have been described in my Patent No. 2,504,993 and my co-pending application previously referred to and will not be detailed here since they do not constitute the subject matter of the present invention.

Each holder element is preferably provided with a slidable spacer or piston member 70 for varying the effective depth of each holder element in order to accommodate articles of varying size. Each holder element is further provided with an auxiliary pivoted retaining member or hold-down bar 71 which is normally urged downwardly against the upper tiltable holder arm 67, as by means of a spring 72, and said hold-down arm (which must be elevated during the application of the label at the affixing station as shown in Fig. 3) serves to retain the secure overlapped ends of the label in position during the interval of movement of the holder element from the label affixing to the ejecting stations of the machine.

The adjustability of lower arm 66 may be achieved by mounting said arm on a rearward extension 66a slidably retained in a slot 73 of main plate 65. A threaded shank 74 depends from extension 66a into operative engagement with a threaded nut or wheel 75 retained within lateral opposed notches 76 formed in main plate 65. Thus lower arm 66 may be adjusted to the desired level depending upon the size of the article being labeled by manipulating the knurled wheel 75. As best seen in Fig. 5, lower arm 66 is preferably provided on its underside with a plurality of longitudinal corrugations 77 serving to eliminate slippage and to assure accurate positioning of the label L as it is extended about the holder element H and the yarn ball Y at the label affixing station of the machine. For similar reasons upper arm 67 is preferably provided with a centrally disposed friction pad 78 of synthetic plastic or other suitable material in order to assure proper alignment of the overlapped ends of the label.

Another feature of the present invention resides in the novel construction of the upper arm 67 of the holder element with a pair of lateral hinge leaves or plates which cooperate with the movable jaw members 15 during compression of the de-

formable yarn ball Y and extension of the label L thereabout. As best shown in Figs. 4 and 6, upper arm 67 comprises a central portion 79 and a pair of lateral hinge leaves 80 pivotally mounted thereon. A light tension spring 81 interconnects said hinge leaves and serves to normally retain them in the inoperative position of Fig. 4. However when the yarn ball is compressed by movable jaw members 15 during the application of the label as shown in Fig. 3, hinge leaves 80 are deflected downwardly against the yarn ball.

Figs. 7 and 8 illustrate an improved ejection mechanism, generally designated by reference numeral 85, for removing labeled articles from holder elements H, said ejection mechanism being operative at a point remote from the label affixing station of the machine. Ejection mechanism 85 includes a slideable member or carriage 86 suitably mounted on the frame of the machine for reciprocation toward and away from a loaded holder element H disposed at the ejecting station of the machine. The reciprocation of the slideable carriage 86 may be accomplished substantially in the manner described in my aforementioned co-pending application or in any other suitable manner. Carriage 86 preferably comprises as an integral structure a pair of side members 86a, a central sleeve-guide 86b and a pair of cam-guides 86c having upwardly divergent extensions 86d. A T-shaped ejector support 87 is slidably retained in sleeve-guide 86b for reciprocation in a vertical path from the lower inoperative position indicated in dotted outline in Fig. 7 to the elevated operative position indicated in full lines in Figs. 7 and 8. Cross member 87a of ejector support 87 carries at its extremities a pair of pivotally mounted ejector arms 88 normally urged toward each other in the position of Fig. 7 by means of a tension spring 89. The lower ends of ejector arms 88 carry followers or pins 90 engageable against cam-guides 86c of carriage 86 during the retraction of ejector support 87 to the dotted line position of Fig. 7.

Ejector arms 88 are designed and constructed in such a manner as to act simultaneously on the yarn ball Y retained on the holder element as well as upon the secured label L in order to more efficiently eject the labeled yarn ball. For this purpose said ejector arms are curved at their upper ends to conform to the contour of upper arm 67 of holder element H and carry at their extremities resilient gripping elements 91 which may take the form of rubber friction pads or the like adapted to overlie and grip the overlapped secured ends of the label. Ejector arms 88 are further provided intermediate their ends with rearwardly and inwardly projecting gripping elements 92 adapted to grip simultaneously the yarn ball or other deformable article and the edges of the label secured thereabout. Ejector support 87 is preferably provided with an auxiliary resilient gripping element 93 or rubber pad adapted to underlie and grip the lower portion of the secured label which is retained against lower arm 66 of holder element H. Gripping element 93 may be carried at the upper end of a spring-backed plunger 94 retained in a holder 95 secured to ejector support 87. It will be understood that with the ejector arms 88 in operative elevated gripping position as described above and shown in Figs. 7 and 8, movement of slideable carriage 86 away from the ejecting station (or to the right as seen in Fig. 8) will be effective to remove the labeled yarn ball from its holder element H.

Since certain modifications may be made in the

label affixing machine of the present invention without departing from the scope thereof, it is intended that all matter contained in the foregoing description and shown in the accompanying drawing be interpreted merely as illustrative and not in a limiting sense.

What is claimed is:

1. In a label affixing machine of the type having means for applying labels circumferentially about the body of a deformable article, a plurality of holder elements having a pair of upper and lower arms for retaining an article therebetween while a label is being extended about said article and said holder arms by said label applying means, and a pair of reciprocable jaw members defining the label affixing station of the machine and adapted to press opposite portions of a partially extended label against respective exposed portions of the article retained on its holder element and to simultaneously compress the deformable article.

2. In a label affixing machine of the type having means for applying labels circumferentially about the body of a deformable article, a plurality of holder elements having a pair of upper and lower arms for retaining an article therebetween while a label is being extended about said article and said holder arms by said label applying means, and a pair of reciprocable jaw members defining the label affixing station of the machine and adapted to press opposite portions of a partially extended label against respective exposed portions of the article retained on its holder element and to simultaneously compress the deformable article, the upper arm of each holder element comprising a fixed central portion and a pair of pivotally mounted side portions engageable by said reciprocable jaw members during the compression of the deformable article and the extension of the label thereabout.

3. In a label affixing machine of the type having means for applying labels circumferentially about the body of a deformable article, a plurality of holder elements having a pair of upper and lower arms for retaining an article therebetween while a label is being extended about said article and said holder arms by said label applying means, a pair of reciprocable jaw members defining the label affixing station of the machine and adapted to press opposite portions of a partially extended label against respective exposed portions of the article retained on its holder element and to simultaneously compress the deformable article, and ejection means operable to remove a labeled article from its supported position on a holder element at a point remote from the label affixing station, said ejection means comprising a pair of pivoted ejector elements having gripping members acting simultaneously on the deformable article and upon portions of the secured label retained against the upper and lower arms of the holder element.

4. In a label affixing machine of the type having means for applying labels circumferentially about the body of a deformable article, a plurality of holder elements having a pair of upper and lower arms for retaining an article therebetween while a label is being extended about said article and said holder arms by said label applying means, a pair of reciprocable jaw members defining the label affixing station of the machine and adapted to press opposite portions of a partially extended label against respective exposed portions of the article retained on its holder element and to simultaneously compress

the deformable article, the upper arm of each holder element comprising a fixed central portion and a pair of pivotally mounted side portions engageable by said reciprocable jaw members during the compression of the deformable article and the extension of the label thereabout, and ejection means operable to remove a labeled article from its supported position of a holder element at a point remote from the label affixing station, said ejection means comprising a pair of pivoted ejector elements having gripping members acting simultaneously on the deformable article and upon portions of the secured label retained against the upper and lower arms of the holder element.

5. In a label affixing machine of the type having means for applying labels circumferentially about the body of a deformable article, a plurality of holder elements having a pair of upper and lower arms for retaining an article therebetween while a label is being extended about said article and said holder arms by said label applying means, and a pair of reciprocable jaw members defining the label affixing station of the machine and adapted to press opposite portions of a partially extended label against respective exposed portions of the article retained on its holder element and to simultaneously compress the deformable article, each of said jaw members having a pivoted hinge member normally maintained in substantially horizontal position for reception of a label and deflectable to substantially vertical position upon movement of a loaded holder element to the label affixing station.

6. In a label affixing machine of the type having means for applying labels circumferentially about the body of a deformable article, a plurality of holder elements having a pair of upper and lower arms for retaining an article therebetween while a label is being extended about said article and said holder arms by said label applying means, and a pair of reciprocable jaw members defining the label affixing station of the machine and adapted to press opposite portions of a partially extended label against respective exposed portions of the article retained on its holder element and to simultaneously compress the deformable article, the upper arm of each holder element comprising a fixed central portion and pair of pivotally mounted side portions engageable by said reciprocable jaw members during the compression of the deformable article and the extension of the label thereabout, each of said jaw members having a pivoted hinge member normally maintained in substantially horizontal position for reception of a label and deflectable to substantially vertical position upon movement of a loaded holder element to the label affixing station.

7. In a label affixing machine of the type having means for applying labels circumferentially about the body of a deformable article, a plurality of holder elements having a pair of upper and lower arms for retaining an article therebetween while a label is being extended about said article and said holder arms by said label applying means, a pair of reciprocable jaw members defining the label affixing station of the machine and adapted to press opposite portions of a partially extended label against respective exposed portions of the article retained on its holder element and to simultaneously compress the deformable article, and ejection means operable to remove a labeled article from its supported position on a holder element at a point remote from the label

affixing station, said ejection means comprising a pair of pivoted ejector elements having gripping members acting simultaneously on the deformable article and upon portions of the secured label retained against the upper and lower arms of the holder element, each of said jaw members having a pivoted hinge member normally maintained in substantially horizontal position for reception of a label and deflectable to substantially vertical position upon movement of a loaded holder element to the label affixing station.

8. In a label affixing machine of the type having means for applying labels circumferentially about the body of a deformable article, a plurality of holder elements having a pair of upper and lower arms for retaining an article therebetween while a label is being extended about said article and said holder arms by said label applying means, a pair of reciprocable jaw members defining the label affixing station of the machine and adapted to press opposite portions of a partially extended label against respective exposed portions of the article retained on its holder element and to simultaneously compress the deformable article, the upper arm of each holder element comprising a fixed central portion and a pair of pivotally mounted side portions engageable by said reciprocable jaw members during the compression of the deformable article and the extension of the label thereabout, and ejection means operable to remove a labeled article from its supported position on a holder element at a point remote from the label affixing station, said ejection means comprising a pair of pivoted ejector elements having gripping members acting simultaneously on the deformable article and upon portions of the secured label retained against the upper and lower arms of the holder element, each of said jaw members having a pivoted hinge member normally maintained in substantially horizontal position for reception of a label and deflectable to substantially vertical position upon movement of a loaded holder element to the label affixing station.

9. In a label affixing machine of the type having means for applying labels circumferentially about the body of a deformable article, a plurality of holder elements having a pair of upper and lower arms for retaining an article therebetween while a label is being extended about said article and said holder arms by said label applying means, and a pair of reciprocable jaw members defining the label affixing station of the machine and adapted to press opposite portions of a partially extended label against respective exposed portions of the article retained on its holder element and to simultaneously compress the deformable article, each of said jaw members having a pivoted hinge member normally maintained in substantially horizontal position for reception of a label and deflectable to substantially vertical position upon movement of a loaded holder element to the label affixing station, and means for temporarily arresting said hinge members in deflected vertical position pending passage of a labeled article on its holder element from the label affixing station.

10. In a label affixing machine of the type having means for applying labels circumferentially about the body of a deformable article, a plurality of holder elements having a pair of upper and lower arms for retaining an article therebetween while a label is being extended about said article and said holder arms by said label applying means, and a pair of reciprocable jaw members

11

defining the label affixing station of the machine and adapted to press opposite portions of a partially extended label against respective exposed portions of the article retained on its holder element and to simultaneously compress the deformable article, the upper arm of each holder element comprising a fixed central portion and a pair of pivotally mounted side portions engageable by said reciprocable jaw members during the compression of the deformable article and the extension of the label thereabout, each of said jaw members having a pivoted hinge member normally maintained in substantially horizontal position for reception of a label and deflectable to substantially vertical position upon movement of a loaded holder element to the label affixing station, and means for temporarily arresting said hinge members in deflected vertical position pending passage of a labeled article on its holder element from the label affixing station.

11. In a label affixing machine of the type having means for applying labels circumferentially about the body of a deformable article, a plurality of holder elements having a pair of upper and lower arms for retaining an article therebetween while a label is being extended about said article and said holder arms by said label applying means, a pair of reciprocable jaw members defining the label affixing station of the machine and adapted to press opposite portions of a partially extended label against respective exposed portions of the article retained on its holder element and to simultaneously compress the deformable article, and ejection means operable to remove a labeled article from its supported position on a holder element at a point remote from the label affixing station, said ejection means comprising a pair of pivoted ejector elements having gripping members acting simultaneously on the deformable article and upon portions of the secured label retained against the upper and lower arms of the holder element, each of said jaw members having a pivoted hinge member normally maintained in substantially horizontal position for reception of a label and deflectable to substantially vertical position upon movement of a loaded holder element to the label affixing station, and means for temporarily arresting said hinge members in deflected vertical position

12

pending passage of a labeled article on its holder element from the label affixing station.

12. In a label affixing machine of the type having means for applying labels circumferentially about the body of a deformable article, a plurality of holder elements having a pair of upper and lower arms for retaining an article therebetween while a label is being extended about said article and said holder arms by said label applying means, a pair of reciprocable jaw members defining the label affixing station of the machine and adapted to press opposite portions of a partially extended label against respective exposed portions of the article retained on its holder element and to simultaneously compress the deformable article, the upper arm of each holder element comprising a fixed central portion and a pair of pivotally mounted side portions engageable by said reciprocable jaw members during the compression of the deformable article and the extension of the label thereabout, and ejection means operable to remove a labeled article from its supported position on a holder element at a point remote from the label affixing station, said ejection means comprising a pair of pivoted ejector elements having gripping members acting simultaneously on the deformable article and upon portions of the secured label retained against the upper and lower arms of the holder element, each of said jaw members having a pivoted hinge member normally maintained in substantially horizontal position for reception of a label and deflectable to substantially vertical position upon movement of a loaded holder element to the label affixing station, and means for temporarily arresting said hinge members in deflected vertical position pending passage of a labeled article on its holder element from the label affixing station.

VINCENT LOBASSO.
